PORTABLE HIGH CHAIR

Homer E. Armitage, Wichita Falls, Tex.

Application July 23, 1956, Serial No. 42,339

Term of patent 14 years

(Cl. D15—1)

Figure 1 is a view in side elevation of a chair showing my new design; the chair shown supported by a table or ledge indicated by broken lines for illustrative purposes only;

Figure 2 is a view in perspective of the chair of Figure 1; and

Figure 3 is a front elevational view thereof.

A characteristic feature of my design resides in the portions shown in solid lines in the drawings wherein the body frames have a double curvature providing a reentrant angle, as an essential point in the ornamental appearance of the design.

I claim:

The ornamental design for a portable high chair, as shown and described.
